TELEPHONE

Fred R. Stafford, Jonesboro, Ind.

Application April 10, 1939, Serial No. 267,077

7 Claims. (Cl. 179—42)

This invention relates to telephones and more especially to a system whereby failure to respond to a call on the main receiving set after a predetermined interval, will result in automatic transfer of the call to a combined party line and extension.

It frequently is necessary, in places of business, to provide the main receiving set with an extension. For example where the main receiver is located in an office it is often useful to have an extension located at a remote point so that the call can be switched onto the extension. It is not desirable, however, under some conditions, to have the bell of the extension ring unless the call is intended for a person in that vicinity. Where a switch arrangement is provided for transferring a call from the main receiver to the extension, the call receives no response if the bell at the main receiver is not heard.

An object of the present invention is to provide means whereby, following a predetermined number of rings on the bell of the main phone, the call will be transferred automatically to the extension where the bell will be sounded.

It is a further object to provide means of this character which are simple in construction and can be installed readily.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings:

Figure 1 is a vertical transverse section through the mechanism constituting the present invention.

Figure 2 is a section on line 2—2, Figure 1, some of the parts being shown in elevation.

Figure 3 is a section on line 3—3, Figure 1.

Figure 4 is a detail view of a portion of the governor-adjusting means.

Figure 5 is a diagram showing the present invention connected to a telephone circuit including a party line.

Referring to the figures by characters of reference, 1 designates a suitable housing which can be in the form of a box having a flange 2 by means of which it can be attached readily to a wall or other support. In this housing is

mounted the mechanism constituting the present invention. It can be assembled in various ways but in the structure illustrated it includes front and back plates 3 and 4 connected by corner posts 5 and, at an intermediate point, by a cross strip 6. To this strip, which is preferably of insulating material is connected the short arm 7 of an L-shaped permanent magnet 8. To this short arm 7 is attached the soft iron core 9 of an electromagnet 10 while hingedly connected to the end portion of the long arm of permanent magnet 8 is an armature 11. A spring 12 serves to hold this armature normally spaced from the adjacent end of core 9 and a pawl 13 is pivotally attached to the free end of the armature 11 and is held by a spring 14 normally pressed against a stop pin 15.

An arbor 15' is journalled in the plates 3 and 4 and rotatably mounted on one end portion of this arbor is a primary ratchet wheel 16 having a hub 17 to which is secured one end of a coiled spring 18 the other end of which is anchored as by means of a pin 19 extending from plate 4. Ratchet wheel 16 is located where it can be engaged and actuated by pawl 13 when the pawl is moved off of its supporting pin 15 and the spring 18 is so arranged as to be placed under increased tension when the ratchet wheel 16 is moved away from its normal position.

A secondary ratchet wheel 20 is secured to arbor 15' so as to rotate therewith. The teeth on this ratchet wheel are pitched oppositely to those on the primary wheel 16 and are adapted to be engaged by a pawl 21 pivotally mounted on one side of the primary ratchet wheel 16 and extended oppositely to pawl 13. A spring 22 can be used for holding pawl 21 normally pressed into engagement with one of the teeth of wheel 20, this spring being mounted in any suitable manner on the wheel 16.

A pin 23 is extended laterally from the primary ratchet 16 and this pin can be used as the mounting for the pawl 21. The pin extends laterally a sufficient distance to engage one side of a switch lever 24 which is pivotally mounted, as at 25 and is adapted to be held in either of two extreme positions at opposite sides of a dead center, by spring 26 constantly thrusting against a pin 27 on the lever and carried by a pivoted link 28 in which the pin is mounted to slide. Thus when lever 24 is pushed in one direction past its dead center it will be held in that position by spring 26 and, when pushed in the opposite direction past its dead center it will be held in that position also by said spring.

The switch controlled by lever 24 includes spaced groups of contacts mounted on suitable supports 29 of insulating material. Lever 24 is positioned between the two groups and each 5 group includes two pairs of contacts. One group includes a pair of resilient contacts 30 and 31 and another group of resilient contacts 32 and 33. Contacts 31 and 33 are connected so as to move simultaneously into or out of engagement with contacts 30 and 32 respectively. The connection, indicated at 34, is of insulating material.

The other group of contacts is similarly arranged, it including a pair of resilient contacts 35 and 36 and another pair of resilient contacts 37 15 and 38. Contacts 36 and 38 are connected so as to move simultaneously into engagement with the respective contacts 35 and 37, the connection, which is of insulating material, being indicated at 39. The two resilient contacts 33 and 38 are 20 located where one or the other of them will be shifted by lever 24, according to the direction in which the lever is moved.

Secured to arbor 15' is a gear 40 in constant mesh with a small gear 41 secured to the rotatable arbor 42 of a governor such as shown, for example, 25 in Figure 2. This governor can include a collar 43 secured to and rotatable with arbor 42 and a brake disk 44 slideable with a sleeve 45 on the arbor. Spring strips 46 connect the collar 43 with sleeve 45 and carry weights 47. Brake shoes in the form of plugs 48 of leather or the like are carried by a plate 49 slideable on and held against rotation by a guide plate 50. This plate 49 is engaged by an adjusting screw 51 having a head 30 35 40 and 52 located where it can be reached readily and by means of the screw the plate can be adjusted so as to move the plugs 48 toward or from the brake disk 44. Thus these plugs or brake shoes can be used for changing the maximum speed at which the governor and the parts controlled thereby can operate.

In Figure 5 the present improvements have been shown by diagram in their proper relation to the main receiving set and party line extension 45 receiving set of a telephone. In this figure one side, L², of a telephone circuit is connected to contact 32 while the other side, L', is connected to contact 30. Contacts 30 and 36 are electrically connected and the same is true of contacts 32 50 and 38. The usual telephone receiver has been indicated generally at M and includes the usual ringer coils 53 which have the same value as the magnet coil 10 to which they are electrically connected as shown. Coil 10 is also connected in 55 series to the main set M through a 1 mfd. condenser. Contact 32 is electrically connected to the main set M, as shown while contact 30 is likewise connected to said set and constitutes a portion of the L' side of the circuit.

60 The extension set of the telephone has been indicated at E and is a duplicate of the set shown at M. The L' side thereof is electrically connected to contact 35, however, while the D² side is electrically connected to contact 37.

65 As before explained the coils 10 and 53 are of equal strength. Thus when the bell of the main set M is operated by the ringing current from L², the armature 11 will be oscillated. This will result in pawl 13 imparting a step by step rotation 70 to the ratchet wheel 16. As this wheel is loose on arbor 15', it will rotate relative thereto and operate to wind spring 18. At the same time pawl 21 will slip over the teeth of the secondary ratchet 20. Following a predetermined number of rings 75 of the bell of the main set M, pin 23 will be

brought against lever 24 so as to push it from the position shown in Figures 1 and 5 to its other extreme position. This will result in breaking the connections between the contacts 30 and 31 and 32 and 33 and will immediately establish electrical connections between contacts 35 and 36 and contacts 37 and 38. Consequently while the main set M will remain in service, the bell current will also be closed to the extension set E. As coil 10 was deenergized at the instant extension set E 10 was brought into service, further actuation of ratchet 16 was stopped. Thus said ratchet is left free to rotate in the opposite direction under the power exerted by the tensioned spring 18 and during this reverse rotation of the primary 15 ratchet, the pawl 21 will carry ratchet 20 therewith. Rotation of the parts under the action of the spring will be retarded, however, by the governor and the parts can be so timed as to allow any predetermined time interval during which 20 the extension E can remain in service. Thereafter, as the ratchet 16 returns to its initial position, the circuit to the extension will be broken by pins 23 shifting lever 24 back to the positions shown in Figures 1 and 5.

Obviously the time period during which the extension phone can be used can be regulated by adjusting the brake shoes 48 so as to permit the governor to rotate at any desired speed.

It will be noted that the arbor 15', the spring 30 and the governor all cooperate to form a spring motor in which ratchet 16 and its pawl constitute the winding means.

By providing a system such as described the operator can call either the main set M or the 35 party or extension set E. If the call on the main set remains unanswered for a predetermined length of time, the bell of set E will begin to ring and thereafter the call can be answered at either station.

What is claimed is:

1. The combination with a telephone circuit including a main set and an extension set, of a motor, a switch, means operated by the bell current to the main set for actuating the switch to 45 simultaneously connect the extension set to the circuit and energize the motor, and means controlled by the motor for actuating the switch to simultaneously disconnect the extension set from said circuit.

2. The combination with a telephone circuit including a main set and an extension set, of a motor, a switch in the circuit, means operated by the bell current to the main set for actuating the switch to simultaneously connect the extension 55 set and to successively energize and release the motor, said motor, when released, constituting means for actuating the switch to disconnect the extension set.

3. The combination with a telephone circuit 60 including a main set and an extension set, of a spring motor, a switch in the circuit normally positioned to close the circuit to the main set, means operated by the bell current to the main set for winding the spring motor and effecting a delayed 65 actuation of the switch to close the circuit to the extension set, said motor being released for operation by the closing of the circuit to the extension, and means controlled by the motor when released, for reversing the switch to break the 70 circuit to the extension set.

4. The combination with a telephone circuit including a main set and an extension set, of a spring motor, a switch in the circuit normally positioned to close the circuit to the main set, 75

- means operated by the bell current to the main set for winding the spring motor and effecting a delayed actuation of the switch to close the circuit to the extension set, said motor being released for operation by the closing of the circuit to the extension, means controlled by the motor when released, for reversing the switch to break the circuit to the extension set, and adjustable means for retarding the operation of the released motor, thereby to delay the reversal of the switch.
5. The combination with a telephone circuit including a main set and an extension set, of a switch in said circuit for maintaining the main set normally connected, a coil connected in parallel with the ringer coils of the main set and of the same strength as said coils, an armature mounted for actuation by the coil, a spring motor, means operated by the armature for winding the motor and for shifting the switch to connect the extension set, the said coil being adapted to be energized by the bell current to the main set, thereby to actuate the armature, the said coil being deenergized when the circuit to the extension set is closed, thereby to release the motor for operation under its own power, said motor constituting 5 means, when released, for reversing the switch to disconnect the extension set, and adjustable means for retarding the operation of the released motor following its release.
10. The combination with a telephone circuit including a main set and an extension set, of a switch in said circuit for maintaining the main set normally connected, a coil connected in parallel with the ringer coils of the main set and of the same strength as said coils, an armature mounted for actuation by the coil, a spring motor, means operated by the armature for winding the motor and for shifting the switch to connect the extension set, the said coil being adapted to be energized by the bell current to the main set, thereby to actuate the armature, the said coil being deenergized when the circuit to the extension set is closed, thereby to release the motor for operation under its own power, said motor constituting 10 means, when released, for reversing the switch to disconnect the extension set, and adjustable means for retarding the operation of the released motor following its release.
15. The combination with a telephone circuit including a main set, an extension set, said sets having independent bell circuits, and a switch in the circuit for maintaining the extension set normally disconnected from the main set, of a coil connected in parallel with the ringer coils of the main set and of the same strength as said coils, thereby to be energized as the bell-ringing current to the main set is closed, an armature oper- 15
20. The combination with a telephone circuit including a main set, an extension set, said sets having independent bell circuits, and a switch in the circuit for maintaining the extension set normally disconnected from the main set, of a coil connected in parallel with the ringer coils of the main set and of the same strength as said coils, thereby to be energized as the bell-ringing current to the main set is closed, an armature oper- 20
25. The combination with a telephone circuit including a main set, an extension set, said sets having independent bell circuits, and a switch in the circuit for maintaining the extension set normally disconnected from the main set, of a coil connected in parallel with the ringer coils of the main set and of the same strength as said coils, thereby to be energized as the bell-ringing current to the main set is closed, an armature oper- 25
30. The combination with a telephone circuit including a main set and an extension set, said sets having independent bell circuits, of a switch for maintaining the main set normally connected, a coil connected in parallel with the ringer coils of the main set and of the same strength as said coils, an armature mounted for actuation by the coil, a spring motor, means operated by the armature for winding the motor and for shifting the switch to connect the extension set to the main set, the said coil being adapted to be energized by the bell current to the main set, thereby to actuate the armature, the said coil being deenergized when the circuit to the extension set is closed, thereby to release the motor for operation under its own power, said motor constituting 30
35. The combination with a telephone circuit including a main set and an extension set, said sets having independent bell circuits, of a switch for maintaining the main set normally connected, a coil connected in parallel with the ringer coils of the main set and of the same strength as said coils, an armature mounted for actuation by the coil, a spring motor, means operated by the armature for winding the motor and for shifting the switch to connect the extension set to the main set, the said coil being adapted to be energized by the bell current to the main set, thereby to actuate the armature, the said coil being deenergized when the circuit to the extension set is closed, thereby to release the motor for operation under its own power, said motor constituting 35
